UNITED STATES PATENT OFFICE.

ARTHUR CUTHBERT, OF LONDON, ENGLAND.

CYCLE-SADDLE.

SPECIFICATION forming part of Letters Patent No. 674,199, dated May 14, 1901.

Application filed April 26, 1900. Serial No. 14,470. (No model.)

To all whom it may concern:

Be it known that I, ARTHUR CUTHBERT, a subject of the Queen of England, residing at London, England, have invented certain new and useful Improvements in Cycle-Saddles, (for which application has been made for Letters Patent in Great Britain under No. 20,729, dated October 16, 1899,) of which the following is a specification.

The object of this invention is to provide a saddle or an attachment which may be applied to any ordinary suspension-saddle, the construction of either being such that the fore and central parts of the saddle are prevented from unduly rising when the rear is depressed by the weight of the rider. To effect this, a part of the saddle-cover in advance of the seat portion is connected to the rear of the saddle by a tie, preferably comprising several parts, as hereinafter described. By the arrangement of the saddle in this manner the rider sits upon the lower bones of the pelvis instead of his weight being thrown upon the perineum, as is the case in existing forms of saddles.

The attachment or saddle constructed according to this invention also affords means by which the tension, and consequently the configuration of the saddle, may be readily adjusted to suit the requirements of any rider.

The attachment may also increase the width of the saddle to which it may be applied without involving the usual disadvantages of a broad saddle.

In the accompanying drawings, which illustrate one method of carrying out this invention, Figure 1 is an under side view of a saddle constructed according to this invention. Fig. 2 is a central vertical section of the saddle on the line 2 2 of Fig. 1. Figs. 3, 4, and 5 are details of construction. Fig. 6 is a plan of the saddle with part of the seating removed. Fig. 7 is a central vertical section of the same. Fig. 8 is a transverse section of the saddle on the line 8 8 of Fig. 6. Fig. 9 is a plan of a modified detail, and Fig. 10 is a plan view of another modified detail.

Like letters indicate like parts throughout the drawings.

In an approximately central position beneath the seat portion of the saddle is a strut A¹⁰, which lies at right angles to the central

axis of the saddle and is approximately parallel to the leather cover B. The strut A¹⁰ is carried on one side by two forward ties A', secured one at either end of the strut, their free ends being held by a strap C made fast to the cover B at a point somewhat in advance of the seat portion. The strap C is riveted to the saddle-cover at C⁸, its free end being turned back upon itself and secured by a buckle C⁹, through which the fixed end of the strap may be passed before riveting. The ties A' for convenience may be made in one piece, the central connecting portion A⁷ being engaged by the strap and arranged to lie approximately parallel to the strut A¹⁰. To prevent wear of the strap at that part against which the part A⁷ of the ties bears, a roller A⁸ may be mounted upon the connecting-piece A⁷, so that the strap passes around the roller and does not bear directly upon the ties. The strut A¹⁰ is carried on that side opposite to the ties A' by rear ties A³. These ties are similarly secured one at each end of the strut A¹⁰ and their free ends connected to a nut A⁴, common to both and carried by a bolt A⁵, passed through the cantle-plate D of the saddle. To avoid expense in construction, the rear ties A³ are also formed in one piece, the central connecting portion being looped, so that it may pass beneath and partly surround the bolt A⁵. The nut A⁴ is provided with an extension A⁹, Fig. 5, which extends beneath the looped portion of the ties A³. Each side of the extension A⁹ is recessed at A¹¹, so that the loop of the ties A³ is engaged between the extension and bolt, its ends lying in the recesses A¹¹. By this means the loop is prevented from displacement from the nut by any sudden backward movement of the ties A³ when in use.

The cantle-plate D is made somewhat shorter than usual, as will be seen by referring to the drawings, so that the side pieces B' of the seat are deprived of the usual support given by the same, and in place of this are supported by adjustable links E, pivoted at E' on either side of the strut A¹⁰, and to plates E², riveted or otherwise secured to the parts B' of the cover. The joints at the end of each link E are preferably so arranged that that at E' permits the link E to swing in an approximately vertical plane, while that

between the link E and the plate E², Fig. 8, allows the link to swing in an approximately horizontal plane.

To secure the forward ties A', rear ties A³, and links E to the strut A¹⁰, it is preferred to employ connecting-pieces E⁷, Fig. 4. Each connecting-piece E⁷ comprises a plate provided with orifices E⁸, through which the ends of the different members may be passed and secured by riveting or other convenient means, and on the lower side is a projection or ear E⁹, which extends beneath the strut A¹⁰ when the connecting-piece is in position and prevents it from rising when pulled upon by the ties A' A³.

To render the links E adjustable, they are preferably made in two parts E³ E⁴, one part having a right-hand screw-thread, while the other has a left-hand screw-thread, in order that they may be connected by a screw-threaded sleeve E⁵. Thus by revolving the sleeve E⁵ the length of each link may be adjusted, and a lock-nut E⁶ is provided at one end of the sleeve to secure it in position when the required length of the link has been found. The lock-nut E⁶ is preferably carried by the parts E³ of the link, so that when finally secured against the sleeve E⁵ the part E⁴ may be free to swivel in the sleeve.

It will be seen that the sides of the saddle are supported by the links E between them and the strut A¹⁰ and that by regulating the length of the links the tension of the saddle in a transverse direction can be regulated. To regulate the tension of the same in a longitudinal direction, the length of the ties A' may be adjusted by means of the strap C, and the whole strut A¹⁰, with its lug A⁶, may be drawn nearer to or placed farther from the cantle-plate D by revolving the bolt A⁵ in one direction or the other. To keep the bolt A⁵ in position when adjusted, it is preferably provided with a hexagonal head, which normally rests in a correspondingly-shaped orifice in the cantle-plate. So long as the saddle is in use the bolt is kept firmly down in its place by the weight of the rider; but when there is no weight upon the saddle the bolt is easily pressed backward, so as to disengage its head from the cantle-plate in order that it may be revolved in one direction or the other for adjustment.

It will be seen that the system of parts comprising the strut A¹⁰ and ties A' A³ together form a single tie which connects that part of the saddle which lies between the seat portion and the forward support of the saddle-cover with the rear of the saddle. These parts could be made in one piece pivoted to the forward and rear parts of the saddle, as described, and in the drawings the letter A, Figs. 1 and 2, indicates the entire system forming the connecting-tie whether constructed as shown in these figures or in the figures referred to below or whether formed as a single solid member.

The framing F, which serves to support the

rear and forward ends of the saddle-cover in a well-known manner, may be of any well-known construction and forms no part of this invention, as the strut, ties, and links described above may be applied to any known form of saddle.

The operation of this device is as follows: As the weight of the rider falls upon the seat portion, the latter, together with its sides B', supported by the links E, is depressed, thus causing the strut A¹⁰ beneath it to be lowered and moved slightly to the rear as it swings upon the bolt A⁵. This movement of the strut A¹⁰ will pull upon the forward links A' and so correspondingly depress that part of the saddle-cover to which they are secured by the plate C. The whole of the seat portion by this means is kept approximately flat or only takes a convenient curve instead of the abrupt rise which occurs upon an ordinary saddle from that point on the seat portion on which the bones of the pelvis rest up to the peak of the saddle. It is obvious from the above that in a saddle arranged according to this invention this rise will only take place from that point at which the forward links A' are secured up to the saddle-peak and will thus permit the rider to rest naturally upon the seat instead of his weight being thrown upon the perineum, as is the case in a saddle of the ordinary construction. Further, the sides B' of the saddle being pivoted to the links E and the links pivoted to the strut A¹⁰ at E' in the manner described will oscillate about a transverse axis of the saddle, so that the fore edge of each is depressed when the rider treads down on that side, rising again during the upward movement. Also the strut A¹⁰ being suspended at the rear by the ties A³ and forward by the ties A' the sides B' are free to oscillate about a longitudinal axis of the saddle, so that the whole part B' on one side, as well as its front edge, will be depressed as the rider treads down on that side, the part B' on the opposite side being simultaneously raised through the medium of the connecting-strut and links. By giving this free movement to the sides B' the saddle may be made broader than usual without chafing or hampering the motions of the rider, while at the same time giving additional seating-room.

It will be understood that the strut A¹⁰ and ties A' are not rigidly secured to the connecting-pieces E⁷, but are passed loosely through them and held in place by a head after the manner of wheel-spokes. The bolt A⁵ is free to oscillate in a similar manner in the cantle-plate D.

The tension of any part of the seat portion may be regulated to suit the particular requirements of the individual rider, as by lengthening or shortening the links E the transverse tension of that part of the seat is adjusted, the longitudinal tension being regulated by screwing the bolt A⁵ farther into or withdrawing it from the nut A⁴, which carries the ties

A³. If necessary, the ties A' may also be adjusted by means of their nuts A², as described below, though under ordinary circumstances sufficient adjustment may be obtained by 5 means of the bolt A⁵.

Figs. 6, 7, and 8 illustrate a slightly-modified construction of the saddle, the forward strap, by which the ties A' are secured to the saddle-cover, being dispensed with and replaced by a plate C. The ties A' in this case are not constructed in one piece, but their ends are passed through ears C' on the plate C and secured by a nut A². The forward adjustment of the ties may thus be effected by 15 revolving the nuts A² in one direction or the other, so that the strut is either brought toward the plate C or removed farther from the same. The rear ties A³ may, if preferred, be dispensed with, the strut A¹⁰ being provided 20 with a lug or projection A⁶, adapted to receive the bolt A⁵. The ties A³ may, however, be retained in conjunction with the plate C and may be carried by a nut A⁴, having an extension A⁹, as described with reference to Figs. 25 1 to 5, or may be passed through or secured to a nut, as indicated in dotted lines in Fig.

6. The arrangement of the different ties, links, and strut may, however, be variously modified without departing from the nature 30 of this invention. For instance, the forward ties may be provided with additional facilities for adjustment by securing them to a device, such as that shown in Fig. 9 of the drawings, attached to the plate C. The 35 plate C is in this case formed with two brackets or lugs C², which serve as bearings for a screw C³, and on the screw is mounted a nut C⁴. The nut C⁴ is prevented from revolving with the screw by any convenient 40 means and has a projection or lug C⁵, through which the ends of the ties A' may be passed and secured each by a head on the opposite side to that at which they enter, or the ties A' may be formed in one piece bent at an angle at that part which lies within the lug C⁵. 45 The ties themselves may serve to prevent the nut C⁴ from revolving with the screw C³, or the plate C may be made solid or provided with a central portion C⁶ and the nut flattened on 50 that side which faces the part C⁶, so that it bears against the same. Again, the ties may be modified by constructing them, as shown in Fig. 10, in the form of a flat strip, so that the complete tie A, connecting that part of 55 the saddle just in advance of the seat portion and the cantle-plate D, is formed in two parts hinged together at that point where the links E are attached, the ties A' forming one part and the ties A³ or tie A⁶ forming the other. 60 The fore part of the tie constructed in this manner may be hinged at C⁷ to a nut carried in a similar manner to the nut C⁴ by the plate C, and the links E may be pivoted to the brackets E⁸ on one of the parts. When the 65 frame member is formed in two parts in this manner, they may, if preferred, be made suf-

ficiently stout to permit of the strut A¹⁰ being dispensed with.

It will be understood that this invention is not limited to a complete saddle only in that 70 the parts forming the subject-matter of the invention may be applied to any existing saddle, and any such saddle may be widened, if necessary.

If it is not desired that a cover should 75 envelop the whole saddle, it may cover the seat proper only, the fore part being conveniently held down by riveting to the plate C. Should the cantle-plate of an ordinary saddle be found to interfere with the action of the saddles B', it may obviously be shortened by cutting off the extending portions.

The strut A¹⁰, with its part A⁶, may be made to take any convenient form, so as to avoid fouling the parts of any ordinary cycle-frame, 85 being in this case arched, as shown clearly in Fig. 8, to avoid contact with the central springs of the particular frame shown in the drawings. The ties and links connected with the strut may also of course be so disposed 90 as to avoid collision with the parts of the frame.

What I claim as my invention, and desire to secure by Letters Patent, is—

1. In a cycle-saddle, the combination of a 95 flexible saddle-cover, forward and rear supports for said cover, a longitudinally-arranged tie, means for pivoting one end of the tie to the saddle-cover at a point between the seat portion and the forward support, 100 means for pivoting the other end of the tie to the rear of the saddle, and inflexible links connecting the tie and the sides of the saddle forward of the cantle-plate; substantially 105 as described.

2. In a cycle-saddle the combination of a 110 flexible saddle-cover having side extensions, forward and rear supports for the saddle-cover, a longitudinally-arranged tie, means for pivoting one end of the tie to the saddle-cover at a point between the seat portion and the forward support, and links pivoted to and connecting the side extensions and the tie as set forth.

3. In a cycle-saddle the combination of a 115 flexible saddle-cover, forward and rear supports for the saddle-cover, a forward tie-piece, a rear tie-piece, a pivotal connection between the two tie-pieces, means for securing the free end of the forward tie-piece to the saddle-cover at a point between the seat portion and the front support of the cover and means for securing the free end of the rear tie-piece to the rear of the saddle and pivotal connections between the tie and saddle forward of 120 the cantle-plate, substantially as set forth.

4. In a cycle-saddle the combination of a 125 flexible saddle-cover, forward and rear supports for the saddle-cover, a longitudinally-arranged tie, means whereby the forward end of the tie is secured to the saddle-cover at a point between the seat portion and the front

support of the cover, links pivoted to and connecting the tie and cover forward of the cantle-plate, means whereby the rear end of the tie is secured to the rear of the saddle 5 and means whereby the distance between one end of the tie and that point at which it is secured to the saddle-cover may be adjusted substantially as set forth.

5. In a cycle-saddle the combination of a flexible saddle-cover, forward and rear supports for the saddle-cover, a transverse strut, forward and rear ties, the pivotal connection between one end of each of the ties and the strut, means whereby the free ends of the forward ties are secured to the saddle-cover at a point between the seat portion and the front support of the cover and means whereby the free ends of the rear ties are secured to the rear of the saddle, substantially as set forth.

20. 6. In a cycle-saddle the combination of a flexible saddle-cover, forward and rear supports for the saddle-cover, a transverse strut, forward and rear ties the pivotal connection between one end of each of the ties and the strut, means whereby the free ends of the forward ties are secured to the saddle-cover at a point between the seat portion and the front support of the cover, a screw carried loosely by its head in the rear support of the saddle-cover, a nut on the screw, and means whereby the free ends of the rear ties are secured to the nut substantially as set forth.

35. 7. In a cycle-saddle the combination of a flexible saddle-cover having the side extensions, forward and rear supports for the saddle-cover, a longitudinally - arranged tie, means whereby the forward end of the tie is secured to the saddle-cover at a point between the seat portion and the front support of the cover, means whereby the rear end of the tie is secured to the rear of the saddle, links pivoted one on each side of the tie-piece and free to move in an approximately vertical plane, means whereby the free end 45 of the links may each be secured to one of the side extensions of the saddle whereby each side extension is free to oscillate upon the end of its link about a transverse axis of the saddle-cover, substantially as set forth.

50. 8. In a cycle-saddle the combination of a flexible saddle-cover having the side extensions, forward and rear supports for the saddle-cover, a longitudinally - arranged tie, means whereby the forward end of the tie is secured to the saddle-cover at a point between the seat portion of the front support of the cover, means whereby the rear end of the tie is secured to the rear of the saddle, links pivoted one on each side of the tie-piece and 60 free to move in an approximately vertical plane, means whereby the free ends of the

links may each be secured to one of the side extensions of the saddle, whereby each side extension is free to oscillate upon the end of its link about a transverse axis of the saddle-cover, and means whereby the length of each link may be adjusted substantially as set forth. 65

9. In a cycle-saddle the combination of a flexible saddle-cover having the side extensions, forward and rear supports for the saddle-cover, a longitudinally - arranged tie, means whereby the forward end of the tie is secured to the saddle-cover at a point between the seat portion and the front support of the cover, means whereby the rear end of the tie is secured to the rear of the saddle, a plate secured to each side piece, a screw-threaded pin pivoted to each plate and free to swing in an approximately horizontal plane, screw-threaded pins pivoted one on each side 75 of the tie-piece and free to move in an approximately vertical plane, a right and left hand screw-threaded sleeve adapted to engage the screw-threaded pins on one side of the saddle, a similar sleeve adapted to engage 80 those on the other side, and means for securing the sleeves substantially as set forth.

10. In a cycle-saddle the combination of a flexible saddle-cover having the side extensions, forward and rear supports for the saddle-cover, a transverse strut, forward and rear ties, a pivotal connection between one end of each of the ties and the strut, an adjustable connection whereby the free ends of the forward ties are secured to the saddle-cover 95 at a point between the seat portion and the front support of the cover, a screw carried loosely by its head in the rear support of the saddle-cover, a nut on the screw, an extension on the nut, a recess in the extension, a loop connecting the free ends of the rear ties and adapted to pass over the extension and rest in the recess of the nut, a plate secured to each side extension, a screw-threaded pin pivoted to each plate and free to swing in an 100 approximately horizontal plane, a screw-threaded pin pivoted at each end to the transverse strut and adapted to swing in an approximately vertical plane, a right and left hand screw-threaded sleeve adapted to engage 105 the screw-threaded pins on one side of the saddle, a similar sleeve adapted to engage those on the other side, and means for securing the sleeves substantially as set forth.

In testimony whereof I have signed my 115 name to this specification in the presence of two subscribing witnesses.

ARTHUR CUTHBERT.
